United States Patent

Des. 235,765
Patented July 8, 1975

235,765

PERPETUAL CALENDAR OR SIMILAR ARTICLE

Dennis A. Knaus, Germantown, and Richard E. Wysocky,
Grafton, Wis., assignors to Jos. Schlitz Brewing Com-
pany, Milwaukee, Wis.

Filed Sept. 4, 1973, Ser. No. 393,795

Term of patent 14 years

Int. Cl. D19—03

U.S. Cl. D19—25

FIG. 1 is a front elevational view of a perpetual calendar on similar article showing our new design;

FIG. 2 is a rear elevational view;

FIG. 3 is a right side elevational view;

FIG. 4 is a left side elevational view;

FIG. 5 is a top plan view; and

FIG. 6 is a bottom plan view.

We claim:

The ornamental design for a perpetual calendar or similar article, as shown.
